UNITED STATES PATENT OFFICE.

VICTOR ANGERER, OF RIDLEY PARK, PENNSYLVANIA, ASSIGNOR TO WILLIAM WHARTON, JR., & COMPANY, INCORPORATED, OF PHILADELPHIA, PENNSYLVANIA, A CORPORATION OF PENNSYLVANIA.

COMBINED BRACE AND TIE-PLATE.

1,118,836.

Specification of Letters Patent. Patented Nov. 24, 1914.

Application filed September 13, 1913. Serial No. 789,663.

To all whom it may concern:

Be it known that I, VICTOR ANGERER, a citizen of the United States, residing in Ridley Park, county of Delaware, State of Pennsylvania, have invented certain Improvements in Combined Braces and Tie-Plates, of which the following is a specification.

One object of my invention is to form a combined brace and tie-plate from sheet metal pressed into shape.

A further object of the invention is to so form the tie-plate and brace that spikes can be driven at each side of the tie-plate 15 to engage the outer base flange of the rail.

The invention also relates to improvements in tie-plates which can be used in connection with the guard rail, or as a slide plate for the point rails of switches.

20 In the accompanying drawings:—Figure 1 is a side view of my improved pressed steel brace and tie-plate showing the running rail in dotted lines; Fig. 2 is a plan view; Fig. 3 is a view of a blank before 25 bending; Fig. 4 is a perspective view of the brace and tie-plate; Fig. 5 is a view illustrating a modification, showing the notches in the plate on each side of the brace; Fig. 6 is a side view illustrating the base extended to support a guard rail; and Figs. 30 7 and 8 are views illustrating the method of making the brace when used as a slide plate for the point rails of switches.

Referring in the first instance to Figs. 1 35 to 4 inclusive, 1 is my improved brace and tie-plate; 2 is the running rail illustrated by dotted lines, held to the ties by spikes 3 and 4 also shown in dotted lines, the spikes extending over the inner and outer base flanges 40 of the rail.

The combined brace and tie-plate is made in a single piece pressed into shape in suitable dies, and has a base section 5 on which rests the running rail 2, and a brace 6 which 45 engages the side and underside of the head of the rail and resists any outward lateral strains. The brace section of the plate is narrower than the plate section, as illustrated in Fig. 2, allowing the plate to extend 50 at each side of the brace, as at 7, so that the spikes 3 can be driven at the edge of the base flange of the rail 2, and the head of the spike will overlap the base flange in direct line with the projecting por-

tion 7 of the plate. The plate is perforated 55 at 8 for the reception of the spikes 4, which overlap the inner base flange of the rail, and the outer extension 9 of the brace has spike holes 10 for the reception of the spikes which resist the outward lateral pressure 60 of the rail. The diagonal member 11 of the brace 6 extends to a point near the underside of the head of the rail 2, and has a bearing portion 12. The brace is bent to form a bearing portion 13 which rests directly under and in contact with the head of the rail, and also has a bearing portion 14 resting against the outer lower edge of the head of the rail. The other diagonal member 15 of the brace is bent as shown at 16 to form 70 a reinforce for this member of the brace, making a very substantial and simple construction, and one which can be formed in a press.

Other fastenings, such as bolts or clips, 75 may be substituted for the spikes, without departing from my invention, and the same may be applied to metal ties, or any other ties and track supports beside wooden ties.

The blank, as illustrated in Fig. 3, is first 80 made by punching from a flat plate and then this plate is preferably placed in a press having suitable dies which crimp or shape the narrow portion of the blank into the form of the brace illustrated in Fig. 1. 85

In Fig. 5, I have illustrated a slight modification of the construction shown in Fig. 4, in that I extend the plate 5^a rearwardly and form notches 17 therein at each side of the brace 6^a, for the reception of the spikes 90 which engage the outer base flange of the running rail.

In Fig. 6 I have shown the plate extended as at 5^b so as to support the running rail 2; the brace 6^b being formed to brace the 95 inside of the guard rail 18.

In Fig. 7, I have illustrated a construction of my improved brace and tie-plate in which the plate 5^c is extended to form a slide 19 for the switch rail 20; the portion 100 of the plate forming the slide being greater in thickness than that portion of the plate under the running rail.

Fig. 8 is a view similar to Fig. 7, with the exception that the plate 5^d is of even thickness throughout, and the slide 19^d for the switch rail is formed by pressing up a section of the plate.

By the above description, it will be seen that I can make a very simple and substantial tie-plate and brace from a single piece of metal, which can be cut from a flat sheet, 5 and pressed into shape by suitable dies, and that the plate can be either of sufficient length to extend under the running rail or may project so as to form the slide plate for the split point rail of a switch, or may be used 10 on a guard rail forming a brace for the guard rail and a tie-plate for both the guard rail and the running rail.

I claim:

1. A combined brace and tie plate made 15 of a single sheet of metal cut and bent into shape, having a flat portion extending under the running rail; and a brace portion narrower in width than the plate and bent so as to bear against the under side of the 20 head of the rail and extending inwardly from the plate and reinforced, the plate having holes for the fastening devices and the extension of the brace also having holes for the reception of the fastening devices.
2. A combined brace and tie plate made 25 from a single piece of sheet metal cut and bent into shape and having a plate section for the reception of one or more rails; a brace consisting of two diagonal members of less width than the plate, the said brace 30 member extending under the head of the rail, the extension of the outer brace member, as well as the plate, having holes for the fastening devices, the plate extending 35 on each side of the brace so that the fasten-

ing devices can be located on each side of the brace and will overlap the base flange of the rail and the plate.

3. A brace and tie-plate made of a single sheet of metal cut and pressed into shape, 40 the brace portion of the structure being less in width than the plate which extends under the rail, the brace being shaped on diagonal lines in respect to the base and made hollow, one diagonal member of the brace 45 extending to a point under the head of the rail and having three bearing surfaces which rest respectively against the web and head of the rail, the other member of the brace being reinforced and terminating in 50 an extension perforated for the reception of tie fastenings which resist the lateral strains of the rail.

4. A blank for a tie plate and brace consisting of a rectangular portion which forms 55 the plate; and an extension, less in width than the said portion, projecting from one side of the rectangular portion and tapered to substantially the same width as the plate at its outer end and forming the brace section of the combined brace and tie plate, the plate and the extension having perforations 60 for the fastening devices.

In testimony whereof, I have signed my name to this specification, in the presence of 65 two subscribing witnesses.

VICTOR ANGERER.
